Filed Jan. 17, 1969, Ser. No. 15,387

Term of patent 14 years

Int. Cl. D2—05

U.S. Cl. D2—337

Fig. 1.

*Fig. 2.*FIG. 1 is a side elevational view of a stocking showing my new design, the top of the stocking being slightly expanded and the bottom of the stocking being folded for convenience of illustrations. The side of the stocking opposite that shown is substantially similar thereto and the folded portion is conventional.

FIG. 2 is a perspective view of the stocking on a reduced scale and shown broken away for convenience of illustration.

I claim:

The ornamental design for a stocking or similar article, as shown and described.
